UNITED STATES PATENT OFFICE.

MAX HERING, OF ZITTAU, GERMANY.

WATER-GAGE.

SPECIFICATION forming part of Letters Patent No. 736,518, dated August 18, 1903.

Application filed September 20, 1901. Serial No. 75,871. (No model.)

To all whom it may concern:

Be it known that I, MAX HERING, a subject of the King of Saxony, residing in Zittau, Germany, have invented certain new and useful 5 Improvements in Water-Gages, of which the following is a specification.

My invention has reference to improvements in water-gages for steam-boilers, and relates more especially to means whereby 10 breakage of the gage-glass is prevented almost to a certainty and whereby fragments of the glass if breakage should have occurred are prevented from being scattered around.

According to the present invention the gage-glass is made of comparatively large male or outer diameter and a female or inner diameter usual in gage-glasses, thereby obtaining a relatively thick wall. This thick-walled gage-glass tube is surrounded by a protecting-mantle, preferably of metal, such as brass 15 or the like, which in order to admit of ready inspection of the water-level within the glass tube is provided with cut-out portions. A cap or top nut and a bottom nut are threaded 20 upon the respective ends of the protecting-mantle after washers are placed between them and the glass tube ends, whereby the steam and water tight joints are obtained. The top and bottom nuts are provided with the 25 steam and water inlets, respectively.

In order to make my invention more readily understood, I have illustrated it on the accompanying sheet of drawings, in which—

Figure 1 is a side elevation of a water-gage 35 according to my invention. Fig. 2 represents a vertical longitudinal section through the same. Fig. 3 is a sectional view illustrating my invention attached to a boiler.

Referring to the drawings, *a* is the gage-glass tube with a relatively thick wall.

b represents washers of any suitable material.

c is the top nut provided with an inner thread engaging a corresponding thread upon 45 the outer upper end of the protecting-mantle *f*, which is provided with suitable openings *e*

to allow of ready inspection of the height of the water-level within the gage-glass. Upon the lower end of the mantle *f* threads the bottom nut *d*. The top and bottom nuts *c* and *d* 50 are provided with steam-inlet *g* and water-inlet *h*, respectively. The mantle *f* is provided with right and left hand threads on its opposite ends.

For more tightly packing the gage-glass or 55 for removing it for repairing or other purposes it is only necessary to rotate the protecting-mantle in one or the other direction, whereby the top and bottom nuts are tightened or loosened, respectively.

In Fig. 3 I have shown how my gage may be attached to a boiler, the pipes *g* and *h* in this instance being bent between the gage and the boiler, so as to make them sufficiently flexible to permit the end pieces *c* and *d* to 60 be moved toward and from each other in manipulating the gage, said pipes passing loosely through the heads of brackets *i* and *j*, secured to the boiler *k*. Any other suitable or known means for accomplishing this purpose 65 may be adopted.

What I claim, and desire to secure by Letters Patent, is—

In a water-gage the combination of a relatively thick walled glass tube, a protecting-mantle surrounding the said thick-walled glass tube and provided with inspection-openings, a top nut and a bottom nut threading upon the upper and lower ends respectively of the said protecting-tube, steam and water 75 pipes integral with said nuts, and washers interposed between the ends of the said glass tube and the inner faces of the said top nut and bottom nut, substantially as and for the purpose set forth.

In witness whereof I have hereunto signed my name, this 4th day of September, 1901, in the presence of two subscribing witnesses.

MAX HERING.

Witnesses:

HERNANDO DE SOTO,
PAUL ARRAS.
